UNITED STATES PATENT OFFICE

FRANK J. SCHLEICHER, OF UNIVERSITY CITY, MISSOURI

BOX

Application filed September 10, 1930. Serial No. 480,901.

This invention relates to boxes made of cardboard or other flexible material, and has special reference to means for utilizing integral portions of the box walls as means for attaching the box walls to the bottom of the box, and also for providing an ornamental feature in connection with the margin of the box bottom so as to eliminate the necessity or desirability of using other or separate features to provide this ornamentation.

An object of the invention is to provide an improved box wherein a strip of cardboard or like material, forming the box side has a continuous defined part designed and constructed to be placed in a definite position against a bottom or top wall in order that such strip may be attached at the bottom or top wall in a definite, predetermined relationship in which said strip extends from the bottom or top walls of the box at definite and predetermined distances from the edges of said walls and in a relationship in which the edges of the defined portions of said strip are flush with the edges of said walls and cooperate therewith to form a thickened area or base outside the box and projecting laterally from said strip.

Another object of the invention is to provide an improved box of the type mentioned wherein said strip and/or said defined portion thereof are provided with indicia for guiding the placement of the strip in proper position on the bottom or top wall of the box for attachment thereto.

Other objects and advantages of the present invention will clearly appear from the following description, reference being made to the accompanying drawings, in which

Fig. 1 is a plan view of the rectangular strip from which the side wall of the box is formed.

Fig. 2 is a view looking toward one edge of said strip and showing indicia which are formed to permit the strip to be bent properly and which guide the proper positioning of the strip for attachment to the bottom or top wall of the box.

Fig. 3 is a top plan view of the box with the lid removed, a portion of the defined portion whereby the side wall of the box is at-

tached to the bottom wall being broken away.

Fig. 4 is a side elevation of the box with the lid thereon.

Fig. 5 is an enlarged sectional view on the line 5—5 of Fig. 3, showing the box proper and the lid thereon in assembled relationship.

Fig. 6 is an end view of the strip which forms the side wall of the box.

In the embodiment of the invention shown in the annexed drawings, the bottom wall of the box comprises a sheet 1 of cardboard or other appropriate material. This bottom wall may be made in any desired contour or form, and I do not restrict myself to the one form shown. For the purpose of illustrating one exemplification of the invention I have shown the wall 1 as provided with two lobes 2 and in one edge between the lobes 2 a notch formed with a sharp corner 3 directly or nearly in alignment with the sharp point 4 at the opposite edge of the sheet 1. The entire edge of the sheet 1 is cut with a sharp die so as to provide an ornamental edge which is exposed when the box is completed and which I define as a cut edge. Accordingly, a preferred embodiment of the invention consists of a box in which the bottom wall of the box and the top wall of the lid are of any desired shape and have exposed cut edges, which are defined herein as bottom and top walls having cut edges.

In describing the invention, I specifically describe the box structure with the explanation that the lid structure is the same, the lid being shown in Figs. 4 and 5 of the drawings. The same reference numerals that are applied to the box proper are applied to like parts of the lid with the exponent "a".

The box side wall is preferably formed with a single elongated strip 5 having a defined portion 6 integral with one edge thereof. The edge of the defined portion 6 is cut by a sharp die so as to provide an ornamental cut edge to be laid flush with the ornamental cut edge of the bottom wall 1 of the box. A V-shaped notch 7 is cut in and through the defined portion 6 and has a depth exactly equal to the width of said defined portion 6. That is to say the apex of the V-shaped notch 7 is at the line 8 which is parallel with the cut

edge of the defined portion 6. The line 8 defines the width of said defined portion 6, and constitutes the line along which a bend is formed to lay the defined portion 6 upon the 5 marginal portion of the bottom wall of the box and to extend the strip 5 at right angles from said bottom wall to provide the side wall of the box as shown. The line 8 may be a crease or a score line, as clearly shown in 10 Fig. 6, so as to facilitate the lateral bending of the defined portion 6, if such facility is needed because of the character of the material used. In the assembly of the box element, the wall strip 5 is bent transversely and 15 sharply along the line 9, this bend extending from the apex of the notch 7 to the opposite edge of said strip. The line 9 constitutes an indicium cooperating with the notch 7 to guide the positioning of the strip upon the 20 bottom wall and to prevent said strip from being placed in a position in which the defined portion 6 crosses the plane of the sharp corner 3 opposite which the line 9 must be placed. The sharp corner formed by bending the strip 5 sharply along the line 9 is placed directly on the line from the corner 3 to the point 4.

The defined portion 6 has an extension 10 projecting beyond one end of the strip 5, said 30 extension having an inclined edge 11 intersecting the end 12 of the strip at the line 8. The edge 11 is arranged at such an inclination that when the wall strip 5 is assembled on the bottom wall of the box said edge 11 is 35 upon the line running from the sharp corner 3 to the sharp point 4. The opposite end of the defined portion 6 is formed with an extension 13 similar to the extension 10, and having an edge 14 that abuts against the edge 11 when the side wall of the box is assembled 40 upon the bottom wall.

The end of the strip 5 opposite from the end 11 is provided with an elongation 15 defined from the wall forming portion of the strip 5 by a line 16 which may be visible or 45 not as desired, and which extends from the line 8 to the opposite edge of said strip 5. The line 16 may be a crease or a score line so as to facilitate the bending of the elongation 50 15 to provide an inner lap for the opposite end of the strip and for attachment thereto by glue or other appropriate fastening means. Thus, as clearly shown in Fig. 3 of the drawings, the elongation 15 is bent sharply along the line 16 so as to lie against the inner side of the opposite end of the wall strip 5 to which said elongation is attached by 55 glue or otherwise as desired.

Any or all of the lines 8, 9 and 16, may be 60 score lines or creases if the character of material used makes such score lines or creases desirable, so as to function as indicia for the proper bending of the strip and so as to permit use of the defined portion 6 to attach the 65 side wall to the bottom wall of the box and in

proper relationship thereto, and to permit bending of the elongation 15 for use in attaching together the ends of the wall strips.

In the manufacture of my improved box the bottom wall is cut in the desired shape and, if desired, the cut edge thereof may be left exposed. The bottom wall 1 may be cut in heart shape, or in any other shape, to utilize the principles of the invention. The strip 5 is cut of the desired length and in the shape 70 to provide the defined portion 6 having a width exactly equal to the distance at which the side wall of the box is to be placed inwardly from the edge of the bottom wall and so as to seat upon the marginal portion of the 75 bottom wall and have its edge flush with the edge of said bottom wall. The notch 7 constitutes a guide indicating the bending line of the strip 5 which may also be provided with a visible crease or score line 9 to facilitate the bending and to cooperate with the notch to prevent bending at the wrong place.

The defined portion 6 of the strip 5 is bent laterally and the strip 5 is bent to the proper shape to form the side wall of the box. During attachment of the strip 5 to the bottom wall continuous pressure is applied upon the defined portion 6 to press the same upon the marginal portion of the bottom wall of the box. This pressure holds the defined portion 6 from tearing or breaking which might otherwise occur, and also operates to cause the glue 17 to hold the defined portion 6 upon and in firm connection with the marginal portion of the bottom wall 1. In this assembly 80 the wall strip 5 is bent along the line 9 and said bend is placed on the line running from the sharp corner 3 to the sharp point 4. The edges 11 and 14 abut together as do the edges of the notch 7. The pressure upon the defined portion 6 during the assembling and attachment of the side wall to the bottom wall of the box is considerable and continuous, and is timed so as to apply the pressure at the proper time to prevent the edge of the 85 defined portion 6 from tearing or breaking or otherwise becoming malformed at any point. This assembly of the side wall of the box upon the bottom wall may be obtained in a 90 box making machine adapted for this purpose.

A box of this character may be manufactured at comparatively low cost and produced in an ornamental form with cut exposed edges of the base and of the attaching defined portion 6 of the side wall so as to eliminate the need or necessity of using separate attaching strips for the purpose of obtaining this attachment, or for the purpose of 95 ornamentation. By making the box of coated cardboard a box of highly ornamental appearance may be thus constructed at much lower cost than by other practices with which I am familiar.

I claim:

1. A box comprising a bottom wall having an exposed cut edge including a plurality of angles, in combination with a strip forming an angular side wall, a defined portion integral with and extending laterally from the lower edge of said strip and having a pair of abutting edge portions for each of said angles and also having an exposed cut edge even with said cut edge of said bottom wall, said pairs of abutting edge portions and said exposed cut edge guiding the location of said strip upon said bottom wall for attachment thereto in a relationship in which said exposed cut edges are in the same plane, and means rigidly securing said defined portion to said bottom wall in said relationship.

2. A box comprising a bottom wall having a plurality of angles on its outer edge, in combination with a strip forming a side wall rising from said bottom wall, a defined portion integral with and extending laterally from the lower edge of said strip and having a pair of abutting edge portions for each of said angles and also having an outer edge even with said edge of said bottom wall, said pairs of abutting edge portions and said outer edge of said defined portion of said strip guiding the location of said strip upon said bottom wall for attachment thereto in a relationship in which said outer edge of said strip and said edge of said bottom wall are in the same plane, and means rigidly securing said defined portion to said bottom wall in said relationship.

3. A box comprising a bottom wall having a notch in one edge formed with a sharp corner and having a sharp angular point at the edge opposite from said sharp corner; a wall forming strip bent parallel with the edge of said bottom wall and forming a wall rising from said bottom wall; a defined portion integral with the lower edge of said strip extending laterally and having a notch extending approximately the full width of said defined portion, said strip being bent transversely at said notch in said defined portion and opposite said notch in said bottom wall and the edges of said notch in said defined portion extending inwardly from the sharp corner of said notch in said bottom wall; means securing said defined portion of said strip rigidly in connection with said bottom wall; and means securing together the ends of said strip.

4. A box comprising a bottom wall having in one edge a notch with a sharp corner and having a sharp angular point at the edge opposite from said sharp corner; a wall forming strip bent parallel with the edge of said bottom wall and having its ends opposite said angular point; a defined portion integral with the lower edge of said strip extending laterally and having a notch with abutting edge portions extending inwardly

from said notch in said bottom wall and having abutting end portions extending inwardly from said angular point; means securing said defined portion of said strip rigidly in connection with said bottom wall; and means securing together the ends of said strip.

5. The method of making a cardboard box comprising forming a cardboard bottom wall with a curved edge portion having a sharp corner notch at one side and a sharp point at the opposite side, bending laterally a defined portion of a cardboard strip having a notch intermediate of its ends extending the full width of said strip; bending said strip and said defined portion to a form in which said strip is parallel with the edge of said bottom wall and in which the edges of said notch in said strip are in abutting contact opposite said notch in said bottom wall and the ends of said strip are in abutting contact opposite said sharp point of said bottom wall and the edge of said defined portion is even with the edge of said bottom wall; and simultaneously subjecting said defined portion of said strip and the marginal portion of said bottom wall to pressure sufficient to prevent said defined portion from tearing when said defined portion is bent with said strip as aforesaid.
